FIGURE 2

FIGURE 3

FIGURE 4

FIG. 1 is a perspective view of a combined contact lens solution, lens and water tray case showing my new design, the top being in an open position.

FIG. 2 is a perspective view thereof with the top omitted for disclosure purposes and the hinged case in an open position.

FIG. 3 is an enlarged cross-sectional view taken on line 3—3 of FIG. 1.

FIG. 4 is an enlarged cross-sectional view taken on line 4—4 of FIG. 1, but showing the top closed.

I claim:

The ornamental design for a combined contact lens solution, lens and water tray case, as shown and described.
